UNITED STATES PATENT OFFICE.

ANDREW LITTLE, OF NEW YORK, N. Y.

DESIGN FOR A FONT OF PRINTING-TYPE.

SPECIFICATION forming part of Design No. 16,485, dated January 19, 1886.

Application filed November 12, 1885. Serial No. 182,647. Term of patent 7 years.

To all whom it may concern:

Be it known that I, ANDREW LITTLE, of the city, county, and State of New York, have invented and produced a new and original Design for a Font of Printing Type, of which the following is a specification.

The nature of my design is clearly shown in the accompanying typographic impression, to which reference is made; and it consists of an unshaded ornamental letter the characteristic feature of which, as shown in the B, C, D, E, O, P, Q, and S, may be said to be the scroll-like ornamentation. In the J, L, N, R, T, U, V, X, and Z the curved line with dot termination occurs, as shown.

In the A the upper cross-line has the inclined-line termination at each end, and the cross ornamentation is composed of the inclined lines meeting at a central point. The inclined-line termination also characterizes the F, G, and Z, as shown at the top of these letters.

The H, J, K, M, N, and R are extended below the line. The central ornamentation of the H is similar to that of the A, and the right-hand and left hand portions of the W extend above the central portion.

The character of the design is preserved in the numerals, the symbol "&," the dollar and pound-sterling marks, the punctuation-marks, and the lower-case, the curved line with dot termination being found in the f, g, h, j, m, n, s, t, and y.

Having now described my invention, I claim as new—

The design for a font of printing-type, as described and shown, the same consisting of an unshaded ornamental letter, the B, C, D, E, O, P, Q, and S having the scroll ornamentation, as shown, the J, L, M, N, R, T, U, V, X, and Z having the curved line followed by the dot termination, as shown, the upper cross-line of the A having the inclined line at each end, the cross ornamentation of the A and H composed of the inclined lines meeting at a central point, the inclined-line termination being found in the F, G, and Z, as shown, the H, K, M, N, and R extended below the line, the right-hand and left-hand portions of the W extended above the central portion, and the character of the design preserved in the numerals, symbol "&," and dollar and pound-sterling marks, the punctuation-marks, and the lower-case.

ANDREW LITTLE.
